CLAIM

The ornamental design for a heat exchanger, as shown and described.

DESCRIPTION

FIG. 1 is a perspective view of a fan-cooled heat exchanger according to the present invention.

FIG. 2 is similar to FIG. 1 and shows with particularity a tunnel port for housing a fan motor.

FIG. 3 is a front elevational view of the heat exchanger of FIGS. 1 and 2, with the rear elevational view being a mirror image thereof.

FIG. 4 is a right-side elevational view of the present heat exchanger, with the left-side elevational view being a mirror image thereof; and,

FIG. 5 is a bottom plan view of the present heat exchanger, with the top plan view being a mirror image thereof.

The broken lines shown in the drawings are included for the purpose of illustrating portions of the article that form no part of the claimed design.
